Application February 5, 1951, Serial No. 209,404

10 Claims. (Cl. 270—55)

1

The present invention relates to an automatic machine for gathering inserts and stuffing them into envelopes. More particularly, this invention relates to a novel machine for gathering inserts in nested relation, that is, with the fold portions of folded inserts containing therebetween other inserts to be included in one envelope, and thereafter stuffing each of the nested collections into its envelope.

Prior to the present invention, there has been a great need among business concerns whose normal operations require regular mailing of form letters or inserts and the like to a large number of addresses, for an insert gathering and envelope stuffing machine which can gather inserts and stuff them into envelopes at a relatively high rate of speed and which can operate continuously at this high rate of speed without having frequent stoppages of the machine caused by faulty gathering or stuffing operations.

One of the conventional types of insert gathering and envelope stuffing machines heretofore used is that in which inserts are gathered merely by stacking one insert on top of another in a series of successive operations, and thereafter the stuffing operation is carried out so that each of the collections of loosely stacked inserts is stuffed into its envelope. Machines for gathering inserts in this manner have been constructed which have a relatively high rated output per hour, but when these machines are in use, it is found that their actual output per hour is considerably below their rated output, because frequent stoppages occur as a result of faulty gathering and stuffing operations.

As is believed understood, it is quite difficult to operate without interruptions an insert gathering and envelope stuffing machine which gathers inserts merely by stacking one on top of another, since, in operation, the stacks of inserts must be translated rapidly in intermittent steps and such translation will readily cause misalignment of the inserts in the stacks resulting in jams being created or preventing a collection of inserts from being stuffed into its envelope. The stuffing operation may be difficult to carry out, not only because of misalignment of the inserts, but also because of the rather loose, bulky stack which results from this type of gathering operation.

In order to overcome these difficulties which prevail when using this conventional type of machine, efforts have been made in this field to develop an insert gathering and envelope stuffing machine which gathers the inserts in nested relation between the folded portions of a folded insert

5 thereby providing a compact collection of inserts which can be translated as a single unit and which can be easily stuffed into its envelope. Nesting of the inserts is desirable, not merely because of the improved operation that can be expected from the insert gathering and envelope stuffing machine, but also because of the more favorable effect inserts arranged in this manner have on recipients of this mail.

10 Insert gathering and envelope stuffing machines have been developed which enable inserts to be gathered in a nested relation, but these machines are not constructed and arranged to permit a sufficient number of collections of nested inserts to be made per unit of time in all instances to meet the present requirements of business concerns.

15 Accordingly, it is a primary object of the present invention to provide an insert gathering and envelope stuffing machine which is adapted to gather a plurality of inserts in compact nested collections and to stuff the same into envelopes and which machine is constructed and arranged to permit the nested collections to be assembled by additions resulting from successive deliveries of inserts to a plurality of partially unfolded inserts being translated by said machine, thereby to form said nested collections in a manner necessitating a minimum of mechanical movements and to stuff a maximum number of compact nested collections per unit of time into envelopes.

20 It is another object of the present invention to provide apparatus for use in an insert gathering and envelope stuffing machine, said apparatus being constructed and arranged to permit folded inserts to be partially unfolded and translated with their folded edges in alignment with their paths of movement so that inserts can be assembled within the folded inserts to form nested collections by addition resulting from successive deliveries, said deliveries being made at right angles to the path of movement of the folded inserts to permit compact collections to be formed with a minimum of movements of the various inserts and to form said collections at a relatively high rate of speed.

25 It is another object of the present invention to provide an insert gathering and envelope stuffing machine of the foregoing character which includes means to insure that each of the folded inserts is in proper alignment at its initial point of translation to facilitate receiving thereafter in proper position within its folds successive deliveries of additional inserts, and which machine

2

includes means to arrest movement of the inserts being intermittently translated at fixed locations before the various insert magazines, thereby to insure that the collections of inserts are compactly and neatly arranged permitting them to be readily stuffed into envelopes.

It is still another object of the present invention to provide an insert gathering and envelope stuffing machine of the foregoing character which includes means to separate the inserts stacked in the insert magazines to facilitate removing them singly therefrom during the gathering operation, and other means which function to register an alarm when excessive or insufficient inserts are translated past predetermined locations.

Other objects of this invention will appear in the following description and appended claims, reference being had to the accompanying drawings forming a part of this specification wherein like reference characters designate corresponding parts in the several views.

In the drawings:

Fig. 1 is a fragmentary plan view of the insert gathering and envelope stuffing machine with a portion of the machine at the right being broken away;

Fig. 1A is a sectional view taken on the line 1A-1A showing the location of discharge air apertures in the air conduit which aids in maintaining the partially unfolded inserts in proper positions;

Fig. 2 is a fragmentary plan view of the insert gathering and envelope stuffing machine showing the portion of the machine broken away in Fig. 1;

Fig. 3 is a fragmentary front elevational view of the left end of the machine with various parts broken away or removed to show features of the driving mechanism;

Fig. 4 is a fragmentary front elevational view of the machine, similar to that of Fig. 3, but showing instead the right end of the machine omitted from Fig. 3.

Fig. 4A is an enlarged front elevational view of one of the gripper mechanisms shown in Fig. 4 which are used in transferring envelopes along the machine;

Fig. 5 is a side elevational view of the machine taken from the left side of the machine as seen in Fig. 1;

Fig. 6 is a sectional view taken on the line 6-6 of Fig. 5 with the right portion of the machine broken away and with various elements removed.

Fig. 7 is a sectional view taken on the line 7-7 of Fig. 5 showing the portion of the machine broken away in Fig. 6 and with various elements removed;

Fig. 8 is an enlarged fragmentary sectional view taken on the line 8-8 of Fig. 3, various parts being broken away or removed to facilitate describing the machine;

Fig. 8A is a fragmentary sectional view of the carriage for the insert gathering elements;

Fig. 9 is an enlarged fragmentary sectional view with various elements removed showing the mechanism for actuating the suction cups for removing inserts from the insert magazines and also showing the mechanism for reciprocating the plurality of fingers which convey the inserts to the insert gathering elements;

Fig. 10 is a sectional view taken through the envelope stuffing substation with various elements being removed to facilitate showing the mechanisms which carry out the operations of stuffing the inserts into the envelopes;

Fig. 11 is a schematic diagram of the compressed air and vacuum systems as used in the present machine;

Fig. 12 is an enlarged fragmentary side elevational view taken on line 12-12 of Fig. 1 of the safety devices as used in the present machine; and

Fig. 13 is an enlarged fragmentary plan view of the safety device shown in Fig. 12.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to the drawings, a preferred embodiment of the insert gathering machine can be seen. As will be more fully explained hereinafter, this machine includes a station for gathering inserts in a nested relation and an envelope handling station for preparing the envelopes to permit the nested inserts to be stuffed thereinto.

The envelope handling station includes a table along which the envelopes can be conveyed and a plurality of substations adjacent the surface 30 of the table by virtue of which a plurality of different operations are performed on the envelopes. The first of these substations is located at the forward end of the table and includes an envelope magazine from which envelopes are extracted and delivered singly to its location on the surface of the table where each is engaged by a chain driven gripper mechanism so as to be conveyed through the remaining substations to a discharge magazine.

Immediately after being gripped by a gripper mechanism, each envelope is conveyed through a substation where an operation for slightly creasing the upper edge of the envelope is performed so that the flap of the envelope will be raised slightly, and thereafter, the envelope is conveyed through a substation where a knife, after passing under the slightly raised flap, folds open the flap of the envelope.

Each envelope is then translated with its flap 50 folded open to an inserting substation where its panels are spread apart and held in an open position to facilitate stuffing of inserts thereinto. Each envelope is also located so that it is in a proper position to receive its inserts.

After being stuffed, the loaded envelopes are passed through successive substations where the return address and other desired printed matter can be printed thereon, the flap can be moistened for sealing, the flap closed, and the loaded 60 envelopes can be deposited in a discharge magazine.

The insert gathering operation is carried out at a station which includes another table along which the inserts are gathered and translated to the inserting substation to be loaded into their respective envelopes. This table is disposed in parallel relationship with the table of the envelope handling station and is arranged to permit translation of the inserts in the opposite direction from the direction of translation of the envelopes.

The inserts are translated along the surface of the table by a plurality of insert gathering elements uniformly spaced in tandem on a support 75 member. The latter is arranged to provide in-

termitent linear movement of the inserts. A series of insert magazines are mounted above the table and along the path of linear movement of the inserts so that successive deliveries can be made of the inserts from the series of insert magazines to the insert gathering elements.

In order to provide the desired nesting of the collected inserts for stuffing into the envelopes, the inserts from the first magazine of the series are introduced into the magazine in a folded condition. A mechanism is provided for removing each of the folded inserts singly from the magazine and thereafter depositing the same on the table adjacent the first of the insert gathering elements to be translated thereby. Prior to such translation, a suction cup mechanism is employed to raise the upper panel of the folded insert and to deposit the same on a conduit which extends above the surface of the table partially before the first magazine and before each of the succeeding magazines. This conduit is positioned between the insert gathering elements and the insert magazines so that the first insert can be positioned with its upper fold on the conduit with the opening between the folded panels facing the magazines so as to facilitate the reception therebetween of additional inserts delivered from the succeeding magazines during the translation of the partially unfolded insert.

Air under pressure is discharged from said air conduit downwardly on the lower fold panel of the first insert to press it against the table surface so that succeeding inserts can be delivered between the folds, and as each insert is nested therebetween, it will also be pressed downwardly by the jets of air to facilitate nesting of succeeding inserts. The insert gathering elements will deposit the collections of nested inserts at the insert stuffing substation where the stuffing mechanism will load the collections of nested inserts into their respective envelopes.

The present insert gathering and envelope stuffing machine is designed to gather inserts in nested collections and to stuff such collections into envelopes at the rate of approximately 5000 nested collections per hour. Because of the novel construction and arrangement of the insert gathering machinery, the operation thereof can be continuous with a minimum of stoppages caused by faulty handling of the inserts or faulty stuffing of the collections of nested inserts into their respective envelopes. This will be understood from the more detailed description which follows hereinafter.

Envelope handling station

Referring to Figs. 1 to 5 of the drawings, the envelope handling station 10 can be seen including a table 12 at one end of which is located an envelope magazine 14. The envelope magazine 14 is formed from a plurality of upright members 16 disposed in spaced relation with respect to one another and positioned to form a rectangular enclosure. A plurality of cross members 18 are mounted on the upright members 16 around the inner periphery of the rectangular enclosure to provide a peripheral ledge on which a stack of envelopes of conventional size can be supported.

The table 12 has an opening 20 located centrally of the envelope magazine 14 through which a plate 22 having a pair of suction cups 24 extending above its upper surface can be reciprocated. The plate 22 is bolted to a rod 26 as at 28, and the rod 26 is journaled in the support bracket 30 and is adapted to be reciprocated by the cam

actuated linkage 31. The latter is pivotally mounted on the shaft 32 and has a cam follower (not shown) on its one end in engagement with the cam 33a, Fig. 7, on the cam shaft 33.

5 Each of the suction cups 24 has a flexible conduit 34, fragmentarily shown in Fig. 4, attached to its lower end to provide a vacuum within its cup portion when in a raised position so as to hold the lowermost envelope and to pull the same 10 from the envelope magazine 14 on the return of the suction cups 24 to their normal position shown in Fig. 4.

Pivottally mounted on the shaft 32 is an arm 36 suitably connected to a kicker member 38 which 15 extends upwardly through a slot 39 in the table 12 so that when the envelope, shown in phantom in Fig. 2, has been deposited on the table by the suction cups 24, the kicker member 38 will be actuated to kick the envelope to one of a plurality of gripper mechanisms 40 to be gripped thereby for conveying the envelope to subsequent substations. The linkage 31 is pivotally mounted in the shaft 32 and has a cam follower adapted to 20 follow a cam 33a on the cam shaft 33.

25 Each of the gripper mechanisms 40 is connected to a chain 42 of an intermittently operating drive arrangement which will be described in greater detail hereinafter. As can be seen in Figs. 3 and 4, the chain 42 is an endless chain having the 30 gripper mechanisms 40 uniformly spaced thereon. As each gripper mechanism 40 is pivoted around the wheel 44 adjacent the envelope magazine 14, the jaws of the gripper mechanism are opened to receive the forward end of an envelope which 35 has been kicked from the plate 22 by the kicker member 38.

The jaws of the gripper mechanism 40 are opened by engagement of the rear or movable jaw member 46, which is pivotally connected at 40 47 to the forward or stationary jaw member 48, with the upwardly extending arm member 50. The latter is pivotally connected by link 51 to the lever 52 which is pivotally mounted on the shaft 53 and has a cam follower (not shown) on its 45 end to follow the cam 33c so that the arm member 50 will be raised to engage the movable jaw member 46 and open the same at the proper time to permit the jaws of the gripper mechanism 40 to receive the envelope from the kicker member 38.

The jaws of the gripper mechanism 40 will be 50 closed gripping the envelope therebetween when the gripper mechanism is moved lengthwise through the slot 54 in the table 12 to the substation for creasing the flap of the envelope. As seen in Fig. 2, the creasing device includes a plate 56 bolted as at 58 to an arm 60 pivotally mounted in the brackets 62. The plate 56 has its one end bent upwardly as at 64 to guide the edge of the envelope thereunder. The table 12 has a recessed portion 66 formed therein into which the plate 56 can be lowered when pivoted in the brackets 62. By virtue of the lowering of plate 56 into the recessed portion 66, a pinching action will take place on the upper edge of the envelope being conveyed causing the flap thereof to be slightly raised to facilitate opening of the flap by the knife 66.

70 The pivotal movement of the arm 60 is provided by the rod 68, which is connected at its one end to the outer end 70 of the pivotally mounted arm 60 and at its other end to the one arm of the bell crank 72, which in turn is pivotally mounted on shaft 53 and has on its other arm 74 a cam

follower (not shown) in engagement with the cam 33d, Fig. 7, of cam shaft 33.

The knife 66 is supported by the bracket 76 and is shaped so that as each of the gripper mechanisms 40 conveys an envelope past the knife 66, the flap will be rolled thereunder to a position as shown in phantom at 18, Fig. 2. Prior to reaching this latter position, a safety device 80 is provided for detecting when an envelope flap has not been properly opened or if no envelope is being conveyed.

The safety device 80 includes an arm 82 pivotally mounted at its midpoint and having at its inner end a suitable type of electrical device for determining, when the arm 82 is pivoted, if paper or the like is present between the said electrical device and the metallic table 12. This can be accomplished by providing an electric contact which will engage the envelope flap or in the absence of such flap, will engage the top of the table 12. A suitable wiring circuit (not shown) can be provided so that in the latter situation the circuit will be closed setting off an alarm or stopping the machine. In the former situation, the paper flap will act as an insulating member preventing the circuit from being closed. Thus, if one of the gripper mechanisms 40 has failed to grip its envelope or if the flap of the envelope is not opened properly, the operator of the machine will be warned and can take the necessary corrective steps to avoid subsequent troubles at the insert stuffing substation which is located immediately after the substation containing the safety device 80.

The arm 82 is pivotally actuated by means of rod 84 which extends between the outer end of the arm 82 and a lever 86 pivotally mounted on the shaft 53, and with the lever 86 having a cam follower (not shown) in engagement with the cam 33c of the cam shaft 33. On rotation of cam shaft 33, the lever 86 will be rocked on the shaft 53 causing rod 84 to reciprocate, which, in turn, will pivotally actuate the arm 82.

Following the operation of opening the flap of the envelope, the latter is conveyed by the gripper mechanism 40 to the insert stuffing substation, indicated generally at 88, Fig. 2. Here, the gripper mechanism 40 first releases the envelope to facilitate stuffing of the latter. The releasing operation can be understood by examining the releasing mechanism shown in Figs. 4 and 7.

As shown, an upwardly extending arm member 90 is positioned to engage the movable jaw member 46 of the gripper mechanism 40 when arm member 90 is raised. A pivotal link member 92 and link 94 are operatively connected with the arm member 90 in a similar manner to that of arm member 50, link member 50a and link 51 previously described. By virtue of this construction, the jaws of the gripper mechanism 40 will be held in an open position while arm member 90 is in its raised position. The latter will be raised by the rocking action of the bell crank 96 which has its one arm 98 pivotally connected to the link 94 and its other arm 100 in camming engagement with the cam 33f of the cam shaft 33. Thus, when the cam shaft 33 rotates, the arm member 90 will reciprocate to open the jaws of each gripper member 40 when the latter has moved the envelope to the position shown in phantom at substation 98 in Fig. 2.

Subsequent to the releasing of the envelope by the gripper mechanism 40, the envelope will be opened and positioned for receiving inserts from the insert gathering station. The mecha-

nisms for positioning and opening each envelope will be described hereinafter subsequent to the description of the insert gathering station.

After the envelope has been loaded at the insert stuffing substation 88, it is again regripped by the gripper mechanism 40. As will be understood more fully, the stuffing operation is completed during the time when the camming action of the cam shaft 33 on the bell crank 96 causes the jaws of the gripper mechanism 40 to be in an open position. Thus, when the gripper mechanism regrips the envelope, the latter will have been loaded.

The gripper mechanism 40 then conveys the envelope to a substation for printing information, such as the return address of the sender, and the like, on each envelope. The apparatus for carrying out this operation is not fully shown in the drawings, since its details are not a part of the present invention, and it should be understood that any conventional type of printing apparatus may be employed.

Referring to Fig. 2, a printing roller 102 can be seen above which is mounted a roller 104 and the envelopes will be conveyed by the gripper mechanism 40 between these rollers 102 and 104. The printing roller 102 contains the necessary type thereon (not shown) and this type is inked by a suitable inking roller 106, Fig. 4, adjustably mounted below the printing roller 102. The inking operation is carried out during one phase of the rotation of the said printing roller 102.

Each loaded envelope is conveyed from the print substation to a discharge substation where the envelope is released by the gripper mechanism 40 and deposited on a reciprocable ram 108. Ram 108 is raised and lowered by the rod 100 which is pivotally connected to the crank arm 110. The latter is secured to shaft 112 which in turn has crank arm 114 secured thereto and the end of crank arm 114 has a cam follower (not shown) which follows in the face cam 116a of cam shaft 116. Thus, on rotation of cam shaft 116, the ram 108 will be vertically reciprocated.

Also mounted on cam shaft 116 is a cam 116b which serves to operate a mechanism (not shown) through the linkage 118 for positioning the envelopes on the ram 108 before the latter is raised. A cam 116c is also mounted on cam shaft 116 to actuate a brake arm 120 for applying the brake 122 intermittently to the clutch 124. The latter is part of a conventional type of drive arrangement for intermittently driving the endless chain 42. The clutch 124 is driven by the sector gear 126 which is reciprocated on shaft 128 by the action of the connecting rod 130. The latter is rotated by the crank 132 located on the end of cam shaft 116. It is to be understood, however, that any conventional type of intermittent drive mechanism for driving the endless chain 42 may be used with the present invention.

Insert gathering station

Referring next to Figs. 1 and 5, the insert gathering station 200 can be seen including a table 202 on which the inserts are deposited from a plurality of insert magazines and are conveyed to the insert stuffing substation 88 previously described. The insert magazines comprise a first insert magazine 204 and a plurality of other insert magazines 206.

The insert magazines 204 and 206 are supported at approximately a 45° angle above the surface of table 202 by a plurality of brackets

208. Each of the insert magazines 204 and 206 has a pair of retainer members 210 extending inwardly before the open front thereof for supporting inserts which have been placed therein. Each of the pairs of retainer members 210 are adjustably mounted, as at 212, on any suitable support structure. As is believed apparent, the retainer members 210 support the inserts (not shown) only at the edges of the latter so that each of said inserts (not shown) can be removed from its magazine by the operation of a pivotally mounted mechanism having suction cups which engage the forward insert (not shown) between its ends and removes it from its magazine.

Attention is directed to Figs. 9, 1, and 5 for an explanation of this operation. As seen, each of suction cups 214 is mounted on an arm 216 which in turn is supported in a support member 218. The support member 218 is attached to the shaft 220 for limited rotation therewith. The shaft 220 has an actuating arm 222 secured thereto to which is pivotally connected a linkage 224. The latter in turn is hingedly connected to the cam actuated arm 226 which has its lower end connected to the shaft 228 and which has a cam follower 230 adapted to follow on the cam 232a of the cam shaft 232. Thus, on rotation of cam shaft 232 the suction cups 214 will be reciprocated to intermittently withdraw inserts from the insert magazines 204 and 206.

A vacuum is created in the suction cups 214 immediately prior to the suction cups 214 reaching the raised position shown in Fig. 9. As will be explained more fully hereinafter, conduits from a manifold on the suction side of a vacuum pump extend to each of the vacuum cups 214. A valve, which is cam actuated from the cam shaft 232, will be opened at the proper time to create the vacuum in the suction cups 214 and the valve will be closed when the suction cups 214 have been pivoted to their lowermost position flush with the top of table 202.

While the suction cups 214 are in their lowermost positions, flush with table top 202, a plurality of fingers 240 are actuated to engage the inserts deposited on the table top 202 and convey them along parallel paths to positions over the slot 242 in the table top 202. As best seen in Figs. 5, 8, and 9, the fingers 240 are extensions of the arms 244 which are attached to the transverse pusher bar 246. The latter extends substantially the length of table top 202 and is mounted on a plurality of rollers 248 enabling it to be moved in a horizontal plane toward and away from the slot 242.

The transverse pusher bar 246 is joined to the crank arm 250 of the shaft 252 by a link 254. The crank arm 250 is reciprocated as a result of the action of the eccentric 254 on the cam shaft 232, which eccentric on rotation of cam shaft 232 will reciprocate the connecting rod 256 and crank arm 258 of the shaft 252. Thus, it can be seen that as the cam shaft 232 is rotated, the plurality of fingers 240 and suction cups 214 will be in synchronous movement enabling the inserts to be removed from the insert magazines 204 and 206 and thereafter to be conveyed to a position above the slot 242 for longitudinal translation along the table top 202.

The inserts (not shown) are translated intermittently along the table top 202 by a plurality of insert gathering elements 260, Figs. 1, 2 and 3, which project upwardly through the slot 242 and are carried on a reciprocable bar 262. The latter

is carried in a guide way 264 which is adapted to be raised and lowered by the reciprocating action of the push rods 266, Fig. 3 and Fig. 8. As best seen in Fig. 8, each push rod 266 is reciprocated by one of the ends of the rocker arms 268, which are mounted on shaft 270 and each has its other end in camming engagement with one of the cams 272 of cam shaft 232. By virtue of this construction, the insert gathering elements 260 will be in a raised position to gather inserts deposited over slot 232 when the said insert gathering elements 260 are moved to the right, and on the return stroke thereof, the insert gathering elements 260 will be lowered to pass under the inserts on the table top 202. It is to be understood that the raised portions of cams 272 will be so positioned as to provide the proper timing of the raising and lowering action of the insert gathering elements 260 to correspond with the horizontal reciprocating movements thereof so that the inserts (not shown) will be collected from in front of each of the insert magazines 204 and 206 and translated to the next in the series of the insert magazines 204 and 206 where they will be deposited until another group of inserts can be added thereto from the insert magazines 204 and 206.

The horizontal reciprocating movements of the insert gathering elements 260 for translating the inserts (not shown) to the right is effected by the gear driven mechanism, Figs. 3 and 6, comprising the bevel gears 280 and 282 secured respectively to the cam shaft 232 and the shaft 284 which in turning will rotate the crank 286. The latter is linked to the pivotally mounted arm 288 for oscillating said arm 288 on the journal mountings 290. The upper end of arm 288 is connected to the reciprocable bar 262 by a link 292 so that the reciprocable bar 262 will be reciprocated by the arm 288.

The mechanism for reciprocating the bar 262 is suitably constructed and arranged to permit the bar 262 to be moved from the position shown in Fig. 3 to a position to the right thereof approximately equal to the distance between each of the insert gathering elements 260. By virtue of this construction, the inserts (not shown) can be intermittently translated from a position before one insert magazine to a corresponding position before the next insert magazine. As explained above, after the inserts (not shown) have been deposited before an insert magazine, the insert gathering elements 260 will be lowered below the top surface 202 and then returned to the starting position shown in Fig. 3. The return of the insert gathering elements is effected by the return stroke of the arm 288 in a manner believed to be readily understood.

One of the important features of the present invention is the manner in which the inserts are gathered in nested relationship while being translated along the table 200. The inserts (not shown) which are placed in the insert magazine 204 are in a folded condition with a folded edge uppermost. When an insert (not shown) is removed from the first insert magazine 204, it will be deposited on the table top 202 with the folded edge facing in the direction of the slot 242. Thereafter, when the fingers 240 push the folded insert (not shown) over the slot 242, the folded edge will be adjacent the rail 294.

The folded insert (not shown) will then be partially unfolded by the action of the suction cup 300, which is mounted on the pivotally mov-

able arm 362, and by the action of the suction cups 304 seated in the table top surface 202.

As seen in Figs. 1, 5, and 8, the arm 302 is mounted in a support member 306 which is secured to the shaft 308. The latter is journaled in the bearings 310 and 312 and can be rotated a limited amount as a result of the oscillating motion of depending arm 314. A link 316 is pivotally connected to depending arm 314 and to the one arm of the bell crank 318 which is journaled on the shaft 270. See Fig. 6. The other arm 319 has a cam follower (not shown) at its end in engagement with face cam 319a. Thus, when the bell crank 318 is rotated intermittently, a limited amount by the cam action on the face cam 319a the suction cup 300 will be lowered and raised to lift the upper fold of the folded insert (not shown). The lower fold will be held down by the suction cups 304. It should be understood that a vacuum will be created in each of the suction cups 300 and 304 by the vacuum pump and suitable conduits leading to said suction cups 300 and 304 as will be more fully described herein-after.

The primary purpose of the suction cup 300 is to raise the upper fold of the folded insert (not shown) to a position above the air conduit 320 after which the upper fold can be released thereon to be translated intermittently by the insert gathering elements 260 to positions before each of the succeeding insert magazines 206. As can be seen in Fig. 1, the extension rod 321 of the air conduit 320 extends a short distance in front of the insert magazine 204 so that the right end of the upper fold of the folded insert (not shown) will rest on extension rod 321 when released by the suction cup 300. It is to be understood that the extension rod 321 may be substituted for another of a different length or a telescoping member may be provided if necessary when adapting the present insert gathering machine for gathering inserts of a different length than that contemplated when using the extension rod 321.

The air conduit 320 not only serves as a means for supporting the upper fold of the folded insert (not shown) but in addition, by virtue of the plurality of longitudinally spaced apertures 322 thereon, Fig. 1a, through which air under pressure can be discharged downwardly serves to depress the lower fold of the folded insert (not shown) and each of the inserts deposited between the folds from the succeeding insert magazines 206. Thus, each collected insert will be deposited on top of the proceeding insert and will be inserted between the folds of the first insert gathered by the insert gathering elements 260.

In order to assist in maintaining the gathered inserts in uniform collections, a shield 324, Fig. 1, is positioned before the insert magazine 204 to hold the folded insert (not shown) when the upper fold thereof is being raised, and a plurality of movement arresting devices 326 are located before each of the insert magazines 206 to prevent skidding of the collected inserts following the intermittent forward movement impacted to them by the insert gathering elements 260. The movement arresting devices 326 have a resilient leaf spring 328 under which the inserts can be translated by the insert gathering elements 260, but which will frictionally engage the inserts so that when the insert gathering elements 260 have completed their forward stroke, the resilient leaf spring elements will halt movement of the inserts. It should be understood

that any suitable movement arresting means may be used in place of the devices 326.

Another feature of the present invention which aids in maintaining the nested collections of inserts in compact arrangement is that of having the first insert gathering element 260, which moves before the insert magazine 204, slightly longer than the remaining insert collecting elements. Also, the timing of the raising of the guide way 264 is such that said first insert gathering element 260 will be raised slightly above the top surface 202 near the end of the return stroke of bar 262. In this manner, said first insert gathering element 260 while completing its return stroke will frictionally engage the lower surface of a folded insert (not shown) which has been deposited on the top surface 202 from insert magazine 204, and will square the said folded insert under the shield 324 to insure that said folded insert will be in proper alignment to be translated before each of the succeeding insert magazines 206.

From the foregoing description, it is believed clear that the inserts (not shown) from each of the insert magazines 206 will be collected between the folds of the folded inserts (not shown) from the insert magazine 204 and will be translated by the insert gathering elements 260 to the end of the path of movement indicated at 330, of the last insert gathering element 260. As can be seen in Fig. 2, a guide plate 332 may be employed to aid in guiding the collections of inserts to a position before the plurality of envelope stuffing elements 340, Figs. 2 and 10. Said guide plate 332 directs the inserts against the rail 294 and also depresses the upper fold of the folded insert after said upper fold has dropped over the right end of air conduit 320.

The envelope stuffing elements 340 reciprocate transversely of the path of movement of the insert gathering elements 260 in the slots 342 of the top surface 202 of table 200. The forward ends 344 of the envelope stuffing elements 340 are bifurcated to engage the ends of the folds of the folded inserts as well as the inserts nested therebetween.

The reciprocating motion is imparted to the envelope stuffing elements 340 by the cam 348, Fig. 10, which is a part of cam shaft 232. The cam 346, in rotating actuates the cam follower 348 mounted on one end of bell crank 350 which in turn results in the other arm of the bell crank 350 reciprocating the crank arm 352 by means of link 354. The crank arm 352 is pivotally joined to the carrier 356 which supports the envelope stuffing elements 340 and which travels on suitable tracks 358. As is believed to be readily understood, the cam 348 is mounted in a suitable position on cam shaft 232 so that the envelope stuffing elements 340 will be in a rearward position as seen in Fig. 2 to receive the collected inserts (not shown) from the insert gathering elements 260 and thereafter will move said collected inserts (not shown) forward to the insert stuffing substation 88.

At the insert stuffing substation 88, Fig. 2, a mechanism is provided for opening the envelope (shown in phantom) to receive a collection of nested inserts (not shown). The mechanism includes an air nozzle 360 through which a jet of air is directed at the envelope to spread the upper panel from the lower panel. The source of supply of the air jet will be described more fully hereinafter.

A plate 362 is mounted on a bracket 364 to

limit the spreading of the panels of the envelope and thereby cause the panels to be spread apart at the side edges as well as at the middle. This is to facilitate inserting of the fingers 366 and 368 into the envelope to maintain the panels in spread apart relation while its collection of inserts is being inserted thereinto.

Each of the fingers 366 and 368 are mounted on the lower end of shafts 370 and 372, respectively. The shafts 370 and 372, are each carried in journals 374 and 376 which in turn are supported by a pair of brackets 378 and 380.

Connected to shaft 370 by a crank arm 382 is a link 384 which is pivotally connected at its one end to the rocker arm 386. The latter is pivotally mounted on the bracket member 388 and carries a cam follower 390a at its other end. The cam follower 390a is in following engagement with the cam 390 and the latter is mounted on the cam shaft 392 which is gear driven from the cam shaft 232. By virtue of this construction, the movements of the rocker arm 386 will be synchronized with the movements of the insert gathering elements 268 and the envelope stuffing elements 340.

The fingers 366 and 368 are linked together by a suitable mechanism so that they will be simultaneously pivoted in a clockwise and counterclockwise direction respectively into the open end of the envelope (shown in phantom in Fig. 2) and into engagement with the opposite sides of said envelope, as shown. This mechanism includes the crank arms 394 and 396 and the link 398 pivotally connected at its opposite ends to the ends of said crank arms 394 and 396.

As can be seen, when the link 384 is moved toward the envelope, the crank arm 382 will be turned in a clockwise direction causing the finger 366 likewise to rotate in a clockwise direction. Simultaneous with this action, the crank arm 394 will move link 398 to the right causing crank arm 396 to turn counterclockwise which results in the finger 368 turning counterclockwise. On the return stroke of link 384, the fingers 366 and 368 will each be rotated in opposite directions resulting in their withdrawal from the envelope, as is believed readily understood.

In order to permit the present envelope stuffing machine to be used to load envelopes of different lengths, the bracket 389 has an elongated slot 400 therein in which the shaft 372 is mounted, and an adjustable locking member 402 secures the link 398 to the crank arm 396. Thus, if a group of short envelopes are to be loaded, it is only necessary to loosen the locking member 402 and then move the shaft 372 and its crank arm 396 and finger 368 to the left until the finger 368 is properly located to enter the envelope and engage its right side. From the above description, it can be seen that the fingers 366 and 368 hold the envelopes open during the stuffing operation, but also position each of the envelopes so that it is properly located to receive its collection of nested inserts.

Safety devices

If desired, suitable safety devices may be used at each of the insert magazines 204 and 206 as well as at the insert stuffing substation 83 to stop the operation of the present insert gathering and envelope stuffing machine or to give a suitable warning in the event excessive or insufficient inserts are collected or are stuffed into an envelope.

One such safety device is shown in the drawings and reference is made to Figs. 1, 2, 5, 8, 75

12 and 13 for a description thereof. The device is electrically connected so that when one circuit is completed an alarm will indicate if no insert has passed a particular station, and a second circuit serves to set off an alarm in the event that an excessive number of inserts, determined by their thickness, passes a particular station.

An electric contact 410 is pivotally mounted at 411 on the end of each of the crank arms 412 and is adapted to be raised or lowered by the crank arms 412 when the latter are pivoted by the shaft 414 which is journaled in the plurality of brackets 416. The shaft 414 is caused to rotate by the arm 418 which is rigidly secured to shaft 414 at its upper end and has a cam follower 420, Fig. 6, on its lower end which is adapted to follow on the cam 422. Thus, when the cam follower 420 is on the raised portion of cam 422, the arm 418 will have rotated a limited amount which results in shaft 414 being rotated and thereby, the contacts 410 will be in a raised position with respect to the table 200 permitting inserts to be deposited on table 200 from the insert magazines 204 and 206.

25 When the cam 422 has rotated so that the follower 420 is on the lowered portion thereof, the electric contacts 410 will be lowered to engage the top surface 202 of table 200 or to engage the inserts deposited thereon. If an insert has been properly deposited on the table 200 at each of the contacts 410, each of said inserts will act as an insulator and prevent a circuit from being closed between the contacts 410 and the table 200, and if for any reason an insert was not withdrawn 30 from its insert magazine and deposited on the table 200, a circuit will be completed setting off a suitable alarm (not shown).

As will be understood from the above description, a safety device is provided to set off an alarm 40 in the event there is a failure to collect one of the inserts. This safety device also can be used to set off an alarm (not shown) in the event too many inserts are withdrawn at one time from one of the insert magazines. In order to carry out this operation, an extension member 424 is integrally connected with the pivotal mounting of the electric contact 410. At its outer end, the extension member 424 is spring supported on a support bracket 426 which is secured to the crank arm 412. An adjusting screw 428, also secured to crank arm 412, limits the biasing action of the spring 430 which provides the spring support for extension member 424.

In the event too many inserts are deposited on the table from one of the insert magazines, the thickness of such inserts will cause the electric contact 410 to be pivoted about its pivotal mounting 411 against the biasing action of spring 430, and thus, to lower the outer end of extension member 424 into contact with the electric contact 432, and thereby to set off an alarm (not shown). As can be seen, the electric contact 432 is suitably supported on the bracket 416.

Each of electric contacts 410 and 432 are suitably connected to a source of electric power at low voltage so that when either makes contact with the table top 202 or extension member 424, a circuit will be completed by virtue of the grounding of the contacts setting off the necessary alarm. As is believed to be understood, individual alarms may be used for each of the safety devices so that the operator of the insert gathering and envelope stuffing machine will be able to determine immediately which insert may

have been missed in the gathering operation, or where extra inserts may have been gathered.

If desired, a safety device may also be employed at the insert stuffing station 88 to make certain that only one collection of nested inserts is stuffed into each envelope and to detect instances where no collections of nested inserts are available for stuffing into the envelopes. This safety device is the same in construction as those previously described for use adjacent the insert magazines 204 and 206 and this safety device is identified in Figs. 2 and 5 of the drawings by the reference number 448.

Compressed air and vacuum systems

As is believed understood from the foregoing description, air under pressure is used at various of the substations of the present machine to perform necessary functions in handling the inserts and envelopes. Suction cups are also employed for the same purpose and each of these suction cups are suitably connected to a vacuum source.

Referring to Fig. 11, a schematic diagram of the compressed air and vacuum systems can be seen. A vacuum pump 450 has its suction side joined to a vacuum reservoir 452 by a conduit 454 in which a check valve 456 is located to prevent leakage of air through the pump 450 into the vacuum reservoir 452 when the pump 450 is not in operation.

A manifold 458 is connected to the vacuum reservoir 452, and three conduits 460, 462, and 464 are joined to the manifold 458. The conduit 460 leads to a vacuum valve 464, which is adapted to be opened and closed by the action of cam 466, Fig. 6, on cam shaft 232. Two conduits 470 and 472 lead from the vacuum valve 464, conduit 470 leading to suction cups 304 which are located in the table 200 and conduit 472 leading to the suction cup 300 supported on the pivotally movable arm 302. Thus, it can be seen that a vacuum will be created in suction cups 300 and 304 at the proper time in the cycle of operation of the present insert gathering and envelope stuffing machine since the valve 464 will be controlled by the rotation of cam shaft 232 which controls the movements of the various elements used in gathering and nesting the collections of inserts.

The conduit 462 which leads from the vacuum reservoir 452 extends to the vacuum valve 474 and from there it divides and extends to each of the suction cups 214 which are used to remove inserts from the insert magazines 204 and 206. Only one suction cup 214 is shown in the schematic diagram, but it should be understood that all suction cups 214 are similarly joined by a conduit to vacuum valve 474. The vacuum valve 474 is actuated by the cam 476 which is located on cam shaft 232, Fig. 6.

The conduit 462, which leads from the vacuum reservoir 452 extends to the vacuum valve 476 and from there to the suction cups 24 which are employed in removing envelopes from the envelope magazine 14. The vacuum valve 476 is actuated by cam 478 of cam shaft 232, Fig. 7. Thus, it can be seen that the action of suction cups 214 and also suction cups 24 will be synchronized in their operation with other elements of the machine because the vacuum valves 474 and 476 are actuated as a result of the rotation of cam shaft 232.

The high pressure air used in the present insert gathering and envelope stuffing machine is supplied from the air compressor 480 which dis-

charges into the air reservoir 482 by means of conduit 484. A discharge manifold 486 communicates with said air reservoir 482 and has a plurality of conduits connected thereto, the first conduit 488 extending to the air nozzle 360 at the insert stuffing station 88 for spreading the panels of the envelopes. A high pressure air valve 490 is located in conduit 488 to control flow of high pressure air to air nozzle 360. The air valve 490 is selectively opened and closed by operation of cam 492 of cam shaft 232, Fig. 7.

The second conduit 494 leads from discharge manifold 486 through high pressure air valve 496 to the air conduit 320 located above the top surface 202 of table 200. The opening and closing of air valve 496 is controlled by cam 498 of cam shaft 232.

The third conduit 500 from discharge manifold 486 leads through the high pressure air valve 502 which is arranged to be actuated by cam 503, to the air nozzles 504, which may be used if desired to direct steady flowing jets of air through the apertures 506 in the bottoms of the insert magazines 204 and 206 to spread the inserts in the said magazines 204 and 206, thereby to facilitate removal of the inserts singly from the said magazines.

Air nozzles 508 may also be used, if desired, to aid in spreading the inserts to facilitate removing them singly from the insert magazines 204 and 206. These nozzles 508 receive high pressure air from conduit 510 which is connected to the discharge manifold 482. The air nozzles 508 can be controlled by valve 512 to permit a steady flow of air therefrom at all times so that the inserts in the insert magazines will remain slightly spread apart at all times during operation of the present machine. As stated above, this permits inserts to be removed singly therefrom more readily.

It is believed to be clear from the above description that all movements in the present insert gathering and envelope stuffing machine are effected as a result of rotating cam shaft 232, which either actuates the movable elements through its own cams or actuates them through various gear drives directly connected to cam shaft 232.

An suitable prime mover may be used to rotate cam shaft 232. Referring to Figs. 3 and 5, an electric motor 520 is shown which is connected to the idler shaft 522 by the belt 524 and the idler shaft 522 is connected to cam shaft 232 by a speed reducing gear train 526. A braking device 528 is shown connected to the shaft 530 of electric motor 520 to provide quick stopping of the insert gathering and envelope stuffing machine whenever power is cut off from said electric motor 520. This is a desirable feature, since it will enable the various inserts and envelopes to be retained in their proper places whenever the safety devices, previously described, stop the machine.

Having thus described my invention, I claim:

1. In an insert gathering and envelope stuffing machine, a stationary table, a series of insert magazines, means for delivering inserts simultaneously from the insert magazines to spaced positions on said stationary table, the means associated with the first insert magazine being adapted to deliver a folded insert to its position with the unfolded edge facing its insert magazine, means for positively engaging the upper and lower folded portions and for partially unfolding folded inserts delivered from the first of said insert magazines, a tubular member disposed partially above the first spaced position and

above the remaining spaced positions on said stationary table and on which the upper portion of the folded inserts can be slidably positioned permitting the folded inserts to be translated past the succeeding insert magazines so as to receive in nested relation therein the inserts delivered from said succeeding insert stations, said tubular member having apertures in the lower portion thereof to direct jets of air downwardly to depress the lower half of the folded inserts and the inserts nested thereon, and means to translate the delivered inserts so as to form nested collections by addition resulting from successive deliveries.

2. In an insert gathering and envelope stuffing machine, a stationary table, a series of insert magazines, means for delivering inserts simultaneously from the insert magazines in substantially parallel paths to spaced positions on said stationary table, the means associated with the first insert magazine being adapted to deliver a folded insert to its position with the unfolded edge facing its insert magazine, means for positively engaging the upper and lower folded portions and for partially unfolding folded inserts delivered from the first of said insert magazines, a tubular member partially disposed above the first spaced position and above the remaining spaced positions on said stationary table and substantially normal to the said parallel paths and on which the upper portion of the folded inserts can be slidably positioned permitting the folded inserts to be translated past the succeeding insert magazines so as to receive in nested relation therein the inserts delivered from said succeeding insert stations, and means to translate the delivered inserts so as to form nested collections by addition resulting from successive deliveries.

3. In an insert gathering and envelope stuffing machine, a table, a series of insert magazines, means for delivering inserts simultaneously from the insert magazines in substantially parallel paths to spaced positions on said table, the means associated with the first insert magazine being adapted to deliver a folded insert to its position with the unfolded edge facing its insert magazine, means for positively engaging the upper and lower folded portions and for partially unfolding folded inserts delivered from the first of the series of said insert magazines, a tubular member disposed partially above the first spaced position and above the remaining spaced positions on said table and substantially normal to the said parallel paths and on which the upper portion of the folded inserts can be slidably positioned permitting the folded inserts to be translated past the succeeding insert magazines so as to receive in nested relation therein the inserts delivered from the succeeding insert stations, said tubular member having apertures in the lower portion thereof to direct jets of air downwardly to depress the lower half of the folded inserts and the inserts nested thereon, and means to translate the delivered inserts so as to form nested collections by addition resulting from successive deliveries.

4. In an insert gathering and envelope stuffing machine, a series of insert magazines, means for delivering inserts simultaneously from the insert magazines, means for partially unfolding folded inserts delivered from the first of the series of said insert magazines, means for maintaining each of said folded inserts in a partially unfolded position at the first insert magazine and while being translated past succeeding insert

65

70

75

magazines so as to receive in nested relation therein inserts from such succeeding insert magazines, means to translate the delivered inserts so as to form nested collections by addition resulting from successive deliveries, and means to arrest translating movement of the delivered inserts at a predetermined position before each of the succeeding insert magazines to insure proper positioning of said folded inserts for receiving additional inserts.

5. In an insert gathering and envelope stuffing machine, a table, a series of insert magazines above said table, means for delivering inserts simultaneously from the insert magazines to spaced positions on said table, vacuum cups mounted in said table and thereabove at the delivery position before the first of the series of insert magazines, a tubular member disposed partially above the first spaced position on said table and extending before each of the remaining of the series of insert magazines, actuating means for lowering the vacuum cup mounted above said table into engagement with a folded insert delivered from the first insert magazine while said vacuum cups are in a vacuous state and thereafter raising the upper vacuum cup whereby the upper portion of a folded insert can be raised above said tubular member, and means to translate the partially unfolded insert along said tubular member to form a nested collection of inserts by addition resulting from successive deliveries.

6. In an insert gathering and envelope stuffing machine, a table, a series of insert magazines above said table, means for delivering inserts simultaneously from the insert magazines to spaced positions on said table, a first vacuum cup pivotally mounted above said table at the delivery position before the first of the series of insert magazines, a second vacuum cup mounted in the table at the first delivery position, a tubular member disposed at least partially above the first delivery position on said table and extending before each of the remaining of the series of insert magazines, actuating means for lowering said first vacuum cup into engagement with a folded insert delivered from the first insert magazine while said vacuum cups are in a vacuous state and thereafter raising said first vacuum cup whereby the upper portion of a folded insert can be raised above said tubular member, and means to translate the partially unfolded insert along said tubular member to form a nested collection of inserts by addition resulting from successive deliveries.

7. In an insert gathering and envelope stuffing machine, a table, a series of insert magazines above said table, means for delivering inserts simultaneously from the insert magazines to spaced positions on said table, a first vacuum cup pivotally mounted above said table at the delivery position before the first of the series of insert magazines, a second vacuum cup mounted in the table at the first delivery position, a tubular member disposed partially above the first delivery position on said table and extending before each of the remaining of the series of insert magazines, actuating means for lowering said vacuum cup into engagement with a folded insert delivered from the first insert magazine while each of said vacuum cups are in a vacuous state and thereafter raising said first vacuum cup whereby the upper portion of a folded insert can be raised above said tubular member, means to translate the partially un-

folded insert along said tubular member to form a nested collection of inserts by addition resulting from successive deliveries, said tubular member having apertures in its lower portion for directing jets of air downwardly against the lower portion of said partially unfolded insert and the inserts nested therein, and means for supplying air under pressure to said conduit.

8. In an insert gathering and envelope stuffing machine, a series of insert magazines, means for delivering inserts simultaneously from the insert magazines, means for positioning folded inserts delivered from the first of the series of insert magazines to permit subsequent partial unfolding and depositing thereof on a rail member with the openings of the folded inserts facing the insert magazines, said rail member partially overlapping the place of delivery of the first magazine and extending over the place of delivery of the remaining magazines, means for positively engaging upper and lower portions of folded inserts delivered from the first magazine and partially unfolding the same and depositing the upper of the folded portions on said rail member, said last named means including a pivotally mounted vacuum cup for positively engaging said one portion to move it over the overlapping end of the rail member and a stationary vacuum cup mounted in the place of delivery of the first magazine for holding the other folded portion in place during the unfolding operation, and means to translate the delivered inserts so as to form nested collections by addition resulting from successive deliveries.

9. In an insert gathering and envelope stuffing machine, a table, a series of insert magazines above said table, air nozzles disposed at each of said magazines and adjacent the discharge end thereof for directing jets of air between inserts therein to facilitate removal of inserts therefrom, means for delivering inserts simultaneously from the insert magazines to spaced positions on said table, a first vacuum cup pivotally mounted above said table at the delivery position before the first of the series of insert magazines, a second vacuum cup mounted in the table at the first delivery position, a tubular member disposed partially above the first delivery position on said table and extending before each of the remaining of the series of insert magazines, actuating means for lowering said vacuum cup into engagement with a folded insert delivered from the first insert magazine while each of said vacuum cups are in a vacuous state and thereafter raising said first vacuum cup whereby the upper portion of a folded insert can be raised above said tubular member, means to

translate the partially unfolded insert along said tubular member to form a nested collection of inserts by addition resulting from successive deliveries, said tubular member having apertures in its lower portion for directing jets of air downwardly against the lower portion of said partially unfolded insert and the inserts nested therein, and means for supplying air under pressure to said conduit.

10. In an insert gathering and envelope stuffing machine, a table, a series of insert magazines above said table, means for delivering inserts simultaneously from the insert magazines to spaced positions on said table, a first vacuum cup pivotally mounted above said table at the delivery position before the first of the series of insert magazines, a second vacuum cup mounted in the table at the first delivery position, a tubular member disposed partially above the first delivery position on said table and extending before each of the remaining of the series of insert magazines, actuating means for lowering said vacuum cup into engagement with a folded insert delivered from the first insert magazine while each of said vacuum cups are in a vacuous state and thereafter raising said first vacuum cup whereby the upper portion of a folded insert can be raised above said tubular member, means to translate the partially unfolded insert along said tubular member to form a nested collection of inserts by addition resulting from successive deliveries, said tubular member having apertures in its lower portion for directing jets of air downwardly against the lower portion of said partially unfolded insert and the inserts nested therein, means for supplying air under pressure to said conduit, and means located along the paths of movement of said inserts for detecting passage of insufficient or excessive inserts.

ZENAS E. COLBY.
